ATTORNEYS.

UNITED STATES PATENT OFFICE.

OSSIP JOSEPH WALINSKY, OF SEA GATE, NEW YORK, ASSIGNOR TO WHITE LUGGAGE CO. INC., OF NEW YORK, N. Y., A CORPORATION OF NEW YORK.

LUGGAGE CARRIER.

Application filed December 22, 1925. Serial No. 76,944.

This invention relates to luggage carriers and more especially to hat boxes. In hat boxes now offered commercially a collar is provided within the box, to which 5 collar is sewed the binding and the lining is glued to the binding. The stay for limiting the swing of the cover is separately attached to the collar generally by riveting. With this type of construction it is necessary 10 first to attach the binding to the collar and mount it in the box after which the lining is separately arranged within the box and glued to the binding, the majority of the operations being performed within the 15 box. Where the lining is glued to the binder the surface becomes rough when the glue hardens, giving it an undesirable finish both as to appearance and touch.

An object of this invention is a hat box 20 in which the collar, binding, stay and lining are assembled exterior of the box without glue, thereby materially reducing the labor of assembling, obviating the rough juncture between the lining and binding and 25 also producing a more serviceable and attractive device.

This object is attained by sewing simultaneously to one edge of the collar the lining and binding and also at the same time stitching 30 to the collar one end of the stay. The collar with the binding, lining and stay stitched thereto is then mounted within the box and suitably attached thereto, usually by gluing.

35 Other objects and features of this invention will become apparent from the following specification and accompanying drawings, wherein

Fig. 1 is a perspective view of a hat box 40 embodying the invention,

Fig. 2 is a section on the line 2—2 of Fig. 1 and,

Fig. 3 is a perspective view disclosing the 45 collar, binding, lining and stay previous to their being put in the box.

The box body is designated by 10 and the cover which is hinged to the box is designated by 11. Within the box is provided a collar 12 of cardboard or other suitable 50 material, at the inner upper edge of which may be provided a thin strip 13 of similar material. A binding 14 of velvet or other suitable material, is fitted over the upper edge of the collar 12 embracing the strip

13. Lining 15 extends from the binding 55 to the bottom of the box. The lining and binding are simultaneously stitched, as at 16, to the collar at a point just beyond the strip 13. A stay 17 for limiting the swing of the cover 11 has one end interposed between the lining and binding and is sewed to the collar 12 by the same stitching as the lining and binding.

Fig. 3 shows in detail the above described arrangement. In this figure the lining is 65 shown turned up in the position it is arranged while the stitching operation is being performed. The strip 13 spaces the inner surface of the binding slightly so that when the lining is turned down into 70 normal position the double thickness thereof renders its surface substantially co-extensive with that of the binding, thereby giving a smooth finish to the interior of the 75 box.

After the lining, binding and stay have been sewed to the collar 12, the latter is placed within the box and held in position in any suitable manner such as by gluing. The lining 15 is positioned around the inner 80 surface of the box and its lower end fastened to the bottom of the box by gluing or in some other suitable manner after which the lining for the bottom of the box is put in. With this arrangement practically all 85 of the operations affecting the lining, binding and stay are performed before these elements are put in the box, thereby making it easier for the operator and reducing the time consumed in the operations. Moreover a much more serviceable and attractive 90 juncture between the lining and binding is produced, the usual rough surface at the juncture being entirely obviated.

It is understood of course that various 95 modifications may be made in the structural features of the device above described without in any way departing from the spirit of the invention as set forth in the appended claims.

What I claim as new and desire to secure by Letters Patent is:

1. A hat box comprising a body having 105 a cover hinged thereto, a collar of stiff material arranged within said body in contact with the inner periphery thereof, said collar being of greater width than the depth of said body whereby one edge of the collar

projects beyond the edge of said body, a binding member covering that part of the collar projecting beyond said body, and a lining extending from said binding member to the bottom of said body and being fastened thereto, both edges of said binding member and the upper edge of said lining being jointly stitched to said collar.

2. In a device of the character described, 19 a collar having a thin strip fastened thereto near one edge, a binding arranged over the edge of said collar and projecting beyond said strip, and a lining, said lining and

binding being jointly stitched to said collar just beyond the edge of said strip. 15

3. In a device of the character described, a collar having a thin strip fastened thereto near one edge, a binding arranged over the edge of said collar and projecting beyond said strip, a lining and a stay, said binding, 20 lining and stay being jointly stitched to said collar just below the edge of said strip.

In testimony whereof, I have signed my name to this specification.

OSSIP JOSEPH WALINSKY
